HEALTH SCALE

Henry De S. Lauve, Grosse Pointe, Mich., assignor to Fairbanks, Morse & Co., Chicago, Ill., a corporation of Illinois

Application June 12, 1958, Serial No. 51,327

Term of patent 14 years

(Cl. D52—10)

Fig. 1 is a perspective view of a health scale showing my new design;

The dominant features of the design reside in the portion shown in full lines.

I claim:

The ornamental design for a health scale, as shown and described.
